UNITED STATES PATENT OFFICE.

EDWARD J. RELPH, OF CHICAGO, ILLINOIS, ASSIGNOR TO TAYLOR SIGNAL COMPANY, OF BUFFALO, NEW YORK, A CORPORATION OF NEW YORK.

RAILWAY-SIGNAL.

SPECIFICATION forming part of Letters Patent No. 759,310, dated May 10, 1904.

Application filed August 13, 1903. Serial No. 169,340. (No model.)

To all whom it may concern:

Be it known that I, EDWARD J. RELPH, a subject of the King of Great Britain, residing at Chicago, Illinois, have invented certain new and useful Improvements in Railway-Signals, of which the following is a full, clear, and exact description.

My invention relates to railway-signals, and more especially to the improved construction 10 of the signal-blade or semaphore proper.

To this end my invention consists of the mechanism and construction shown in the accompanying drawings, in which—

Figure 1 is an elevation of my invention, 15 showing the signal at "danger." Fig. 2 is a similar view showing the signal at "safety."

It will be seen that in the drawings I have shown my invention as applied to a dwarf signal, and while it is peculiarly adaptable to 20 such use it is also capable of use in connection with an ordinary signal.

1 is a post, preferably of metal, which carries the signal.

2 is a case containing the mechanism for operating the signal.

3 is an ordinary signal-lantern, which is carried by the bracket 4, mounted upon the standard or post 1.

5 is a shaft, (shown in dotted outline in the drawings,) which is journaled in a cap to the post 1 and to which is transmitted motion in rotation over a small arc of a circle from the mechanism contained within the casing 2. Any desirable form of mechanism may be employed to cause this motion.

6 is a disk, which is rigidly mounted upon a plate 7, which is shown in dotted outline. This plate 7 is rigidly mounted in turn upon a shaft 5. The disk is shown as eccentrically mounted, although the mounting may be concentric with the disk, the purpose of the eccentric mounting being to economize space. The disk 6 carries a band of color 8 across its face, the color of which may be made to suit the use of the signal desired, the color red being indicated in the drawings. The rest of

the disk 6 is white enamel, so as to give sharp contrast between it and the color-band. Rotation of the disk 6 upon the shaft 5 will shift this band from the danger position 50 (shown in Fig. 1) to the safety position. (Shown in Fig. 2.) The disk 6 also carries glass disks 9 and 10, which are so mounted upon it that when the signal is in one position one disk will be concentric with the lamp-lens 55 and when the signal is in the other position the other disk will be in a similar position with reference to the lamp-lens.

It will thus be seen that the signal, particularly in the case of the dwarf signal, results 60 in much economy of space, does away with flexible signals, is simple in construction, and easy of operation. It presents a bold and striking outline, the color-band showing up clearly against the white background, and prevents confusion with surrounding external parts of the signal.

Having thus described my invention and its method of operation, what I claim is—

1. In combination with a signal-post and operating mechanism, a disk, a shaft, said disk being mounted in rotation with said shaft, means for rotating said shaft over an arc of a circle, a color-band extending across the face of said disk in contrasting color with the remaining surface of said disk, a signal-lantern carried on said post and two lenses mounted on said disk, and so positioned that when the disk is in one position one lens registers with the lantern-lens, and when the disk is in the 80 opposite position, the other lens registers with the lantern-lens, substantially as and for the purposes set forth.

2. A railway-signal comprising a disk capable of rotation over an arc of a circle, a color-band extending across the face of the disk, and the remaining portion of the face of the disk being of contrasting color, and means for rotating said disk, substantially as and for the purposes set forth.

3. A signal - disk, comprising, a circular plate and means for rotating the same, a color-

band across its face and contrasting with the color of the face of the signal to constitute a day-signal, and lenses mounted upon said disk of contrasting color, capable of registration with the lantern-lens, to constitute a night-signal, substantially as and for the purposes set forth.

In witness whereof I have hereunto set my hand, in the presence of two witnesses, this 30th day of July, 1903.

EDWARD J. RELPH.
